FILM GAUGE

Clarence W. Morse, Santa Monica, Calif., and
Hans Christian Deichert, Youngstown, Ohio;
said Deichert assignor to said Morse

Application December 7, 1946, Serial No. 714,762

2 Claims. (Cl. 91—53)

1

This invention relates to a device for gauging or controlling the thickness or uniformity of a film or coating on a web, band or like elongated member.

An object of the present invention is to provide simple and effective means for receiving a web which has been coated by being sprayed or otherwise coated with a fluid medium and passing the coated web therethrough to accurately distribute the film-like coating so that it is of uniform and desired thickness.

Another object of the invention is to provide a coating gauging device which functions independently of the thickness of the web to provide a coating which is uniform in thickness throughout the length of the web even under conditions of varying thicknesses of the web.

Another object of the invention is to provide a device of the type indicated which is readily adapted to gauge either one- or both-sided film coated webs.

Our invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration and example only.

In the drawings, like reference characters designate similar parts in the several views.

Fig. 1 is a top plan view of a film or coating gauge embodying the present invention.

Fig. 2 is a vertical sectional view thereof as taken on the line 2—2 of Fig. 1.

Fig. 3 is a similar, but fragmentary sectional view as taken on the line 3—3 of Fig. 1.

Fig. 4 is a fragmentary plan sectional view as taken on the line 4—4 of Fig. 2.

Fig. 5 is a fragmentary perspective detail view of one of the gauge blocks used in the invention.

Fig. 6 is a broken detailed perspective view of a coated web showing the progressive conditions of the coating as controlled by the gauge of this invention.

Generally, the device comprises a relatively fixed gauge block 10, a relatively movable gauge block 11, side blocks or plates 12 connected to the block 10, and means 13 for operatively asso-

2

ciating the blocks 10 and 11 to guide a coated web therebetween and between the blocks 12, laterally.

In practice, the web is moved upwardly between the blocks 10 and 11, as shown, after passing through a conventional dipping tank or after being sprayed or otherwise coated on one or both sides. In the drawing both the web W and the coating thereon have been greatly exaggerated as to thickness, for the purpose of clearer illustration. Under some conditions the web may not exceed a thickness of $\frac{1}{4}$ " or even less and the coating may be as little as .002" or .003". As indicated, the coating, when applied, is in a liquid state and examples of such coating may include emulsions, latex or synthetic rubber, asphalt, ink, paint and various liquid mixtures and compounds.

As shown in the drawing and particularly in Fig. 5, the opposed associated operative faces of each block 10 and 11 are provided with spaced vertical ribs 14 which extend from a bevel 15 to a point 16 from which said ribs slope or otherwise recede as at 17 to blend into a small surface 18 at the top of each block. In this manner, the mentioned face of each block is provided with relatively wide grooves 19 which also extend from the bevel 15 to points 20 in alignment with the points 16. The grooves 19 are then sloped as at 21 reversely to the sloped portions 17 of the ribs to blend into the mentioned wall surface 18. The ribs 14 are therefore of uniform thickness below the points 16 and are gradually tapered from front to back as the wall 18 is approached. It will be evident that a plane projection of the wall 18 will reside between the bottoms of the grooves 19 and the tops of the ribs 14.

The means 13 is shown as comprising two stubs 22 anchored in the outward face 23 of each block 12, extending lips 24 on the movable block 11 and apertured for the studs 22, an adjustable pressure nut 25 on each stud, and a spring 26 on each stud between its nut and the cooperative portion of the lip 24. The nuts can be adjusted to cause the springs to exert pressure urging the described faces of the blocks 10 and 11 toward each other.

In use, the web W is placed between the blocks 10 and 11 as shown and the means 13 adjusted to exert such a pressure as would permit free movement of the web between the blocks in the direction shown by the arrow 27. As seen in Figs. 3 and 4, the ribs 14 are in direct contact with the opposed faces of the web and the block 11 can yieldingly move to take up variations in the thickness of the web or to accommodate splices or other protuberances. It is, therefore, apparent

that webs varying in nominal thickness can be accommodated between the blocks 10 and 11.

The previously coated web is then drawn or passed upward between the blocks. The ribs 14 will shave or wipe away any of the film or coating on the web in contact therewith and leave only such portions of the coating which are opposite the grooves 19. The number 28 indicates these coated portions of the web as it passes through the device. The coating portions 28 fill the grooves 19 and any excess is directed downwardly from the throat formed by the mating bevels 15.

As the web continues upwardly, the receding portions 17 of the ribs 14 together with the oppositely sloped groove portions 21 act to both spread the coating portions 28 and to thin them out. In this manner the portions 28 are changed to resemble trapezoidal areas 29 which diminish in thickness from the narrower to the wider parallel edges. The areas 29 then meet at the lower edge 30 of each surface 18 and the coating then continues upward with the web as a continuous coating 31 having a thickness equal to the difference of level between the ribs 14 and the surface 18 of each block 10 and 11.

The web is definitely located between the blocks and with identical rib and groove formations on both blocks, the coating 31 will be identical for both sides of the web.

If one side only of the web is to be coated, one of the blocks 10 or 11 has the ribs and grooves replaced by a plane surface and the device will function, as set forth, but will produce a film-like coating only on the side of the web which is directed toward the block having ribs and grooves.

For any desired thickness of coating, it is a simple matter to proportion the width-depth ratio of all the grooves to equal the width-thickness area of the finished coating. Stated in other words, the thickness of the finished coating is first determined. The area of a typical cross-section of the coating is then simply calculated by multiplying said thickness by the width of the web. Said area is then apportioned to the number of grooves 19 to be formed in the gauge block. The depth of each groove 19 is therefore made so that the sum of the areas of the grooves equals the area of the finished coating. The transition portions 17 and 21 are then formed to connect the resultant grooves and ribs to the surface wall 18 which is outwardly spaced with respect to the tops of the ribs a distance equal to the thickness of the finished coating.

While we have illustrated and described what we now regard as the preferred embodiment of my invention, the construction is, of course, subject to modifications without departing from the spirit and scope of our invention. We, therefore, do not wish to restrict ourselves to the particular forms of construction illustrated and described, but desire to avail ourselves of all modifications that may fall within the scope of the appended claims.

Having thus described our invention, what we claim and desire to secure by Letters Patent is:

1. A liquid coating thickness controlling device for webs comprising a pair of relatively yieldingly movable blocks, raised rib means on the operative face of each block engaged with the opposed faces of the web to locate the same, and means on at least one of said block faces as a coated web is passed between the blocks for dividing the coating of the web into spaced strips of one thickness, then gradually spreading said strips of coating and simultaneously gradually thinning the same and then connecting the strips to form a uniformly spread coating thinner than the thickness of the strips, and having a cross-sectional area substantially equal to the sum of the cross-sectional areas of the spaced strips of coating.

2. In a device for controlling the uniformity of thickness of the coating of a web, a block having a face formed with ribs of rectangular cross-section and defining grooves therebetween, the outer faces of said ribs being adapted to bear against a previously coated web moving thereby to remove the coating except such portions of the latter that reside in the grooves, said ribs being thicker than the ultimate desired thickness of coating on the web, said grooves thereby having a depth commensurate to the thickness of the ribs, the widths of said grooves being so proportioned that the sum of their cross-sectional areas substantially equals the cross-sectional area of the ultimate coating, a surface on the face of the block spaced from the ends of the ribs and residing in a plane so spaced from the plane of the outer faces of the ribs that the area defined between said planes is substantially that of the sum of the areas of the grooves, a sloping surface on said block face connecting the outer face of each rib with the mentioned spaced surface, and an oppositely sloping surface on said block face connecting the bottom of each groove with said spaced surface, whereby the strips of coating residing in the grooves as the web is moved in a direction toward said spaced surface, are simultaneously and gradually thinned and spread to uniformly coat said web.

CLARENCE W. MORSE.
